H. L. GLIDDEN.
SHOE RACK AND METHOD OF MAKING IT.
APPLICATION FILED DEC. 15, 1916.

1,419,250.

Patented June 13, 1922.

UNITED STATES PATENT OFFICE.

HARVEY L. GLIDDEN, OF NEEDHAM, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE RACK AND METHOD OF MAKING IT.

1,419,250.

Specification of Letters Patent. Patented June 13, 1922.

Application filed December 15, 1916. Serial No. 137,157.

To all whom it may concern:

Be it known that I, HARVEY L. GLIDDEN, a citizen of the United States, residing at Needham, in the county of Norfolk and 5 State of Massachusetts, have invented certain Improvements in Shoe Racks and Methods of Making Them, of which the following description, in connection with the accompanying drawings, is a specification, 10 like reference characters on the drawings indicating like parts in the several figures.

This invention relates to racks and in particular to racks used in shoe factories 15 for transporting unfinished shoes from one place to another.

Shoe racks are a source of considerable trouble and expense. They are frequently made of wood because this material is light 20 and because racks made from it are comparatively cheap. A disadvantage in the use of such racks arises from the fact that the atmosphere in shoe factories varies greatly from room to room and from season 25 to season in regard to dampness and temperature, and wooden racks shrink and swell and soon become rickety and loose at the joints. Their performance under these conditions is unsatisfactory and it is 30 frequently necessary to repair them which entails considerable expenditure. Racks made of metal are not subject to these objections but their expense prevents their use in many factories. Combined wood and 35 metal racks have been proposed, but prior to the present invention did not go into general use owing to the fact that they were so constructed that any impairment of the rigidity of the wooden structure 40 caused loss in rigidity of the whole.

Another objection to the use of wooden shoe racks is the difficulty of replacing a broken member. These racks frequently contain shelves made of dowel rods in order 45 to save material and insure lightness, and these dowel rods are frequently broken. The replacement of a single broken rod often involves dismounting the entire rack which means a loss of considerable time and the 50 incurring of substantial expense.

Shoe racks are also frequently injured in their lower portions below the shelves. They are propelled over rough floors at considerable rates of speed and undergo a good

many collisions with low lying objects, 55 posts, walls and other racks and the lower main frame portions, especially the members carrying their casters, which receive a great many shocks, are frequently broken. The repair of a wooden rack which has been 60 damaged in this way is quite an expensive matter since it often involves the building of a new frame for it and this entails a substantial fraction of the cost of building 65 an entire new rack.

My invention contemplates the provision of a rack having an entirely self supporting metal frame in which the shelf members are confined. In the rack shown in the drawing which embodies an important part 70 of the invention, the shelf members take no part whatsoever in the bonding of the rack, being simply confined by the frame. The shrinking and swelling of the materials of which these members are made can therefore not affect the stability and stiffness 75 of the rack. Any looseness due to shrinkage will merely cause a slight rattling of the shelf members themselves, but will entail no weakness of the rack as a whole. 80

In this respect the invention contemplates not only the building of new racks having the characteristics noted, but also an improvement in the art of making racks which is exemplified in the making of a 85 rack such as previously described and which permits the utilization as shelf structure of parts of damaged wooden racks which would otherwise in many cases be wasted since badly damaged wooden racks are 90 either thrown away or are repaired at substantial expense only to be badly damaged again after relatively short use owing to the easily broken and unprotected wooden structure. The shelf members of wooden 95 racks generally last longer than the base portions, and I shall show how those remaining parts may be used to produce a rack which is better than the original wooden one and which costs much less than 100 the new metal one to which it is practically equivalent.

Accordingly an important feature of the invention consists in a rack having a metal frame comprising base and end portions, 105 with the end portions rigidly interconnected by a combined strut and tie member, thus forming a completely rigid and self-sup-

porting metal frame, and having a wooden shelf structure confined in the frame, preferably without bonding. In the rack shown in the drawing, the end portions of the frame are formed of angle bars with their concave channels facing inwardly and receiving and confining the wooden shelf structure.

Another important feature of the invention consists in a wooden shelf structure comprising interconnected wooden corner verticals supported and nesting in the inwardly facing channels of the metal angle bar verticals.

15 A further important feature of my invention is a shelf which permits the replacement of broken dowels or slats without loss of time or labor in taking the rack apart. This shelf has a slat supporting member, 20 and a second member for holding the slat or dowel in position on the supporting member, and removable to permit the removal or insertion of the slat.

25 The drawings show a preferred form of rack which illustrates the practice of my invention and clearly shows the above described and other advantages which may be realized from the invention. The invention and its advantages will be more fully described in connection with the rack shown, and will be then defined in the appended claims.

In the drawings,

Fig. 1 is a perspective view of the rack; 35 parts being broken away;

Fig. 2 is a view of the end member of a novel shelf;

40 Figs. 3 and 4 are details showing modes of attachment of the upper steel frame member.

45 The base of the rack is formed by parallel angle irons 10 and 12 connected by cross bracing 14. Suitable casters 16 are mounted upon the base and a bumper 18 is mounted at each corner for the purpose of guiding the rack away from posts or other objects with which it may come in contact. A vertical angle iron 20 is mounted at each corner of the base and these four vertical angle irons are braced to the base and to one another by 50 the diagonals 22 and 24 respectively. The angle irons at the ends of the frame are joined by tubular members 26 which are slotted to receive a flange of each angle iron.

55 An upper cross member comprising, in the rack shown, two end angles 28 and 30 and a longitudinal angle 32 braced to the angles 28 and 30 by diagonals 34 and 36 respectively connects the two vertical angles at one end of the frame with those at the other. 60 This cross member may be attached in various ways, of which two are shown. The end member 28 is shown abutting upon the verticals 20 from the inside and clamped thereto by a bolt 38. The end member 30 is shown 65 abutting its pair of verticals 20 from the

outside and clamped to them by a corresponding bolt 40. The metal frame thus far described is self contained and is perfectly rigid, since the member 32 acts both as a tie and as a strut. It will not be affected in any way by atmospheric conditions. The brace structure 28, 30, 32 holds the end frames rigidly against horizontal distortion by virtue of the brace 34, 36, and against vertical distortion by virtue of the substantial vertical extent of the engagement between the members 28 and 30 and the corner verticals. The strut-and-tie member 32 is rigidly fastened to the end frames, and resists any stress tending to move it out of perpendicularity to the end frames.

75 Each vertical 20 carries a little angle 42 for supporting the shelves of the rack. These shelves which, taken collectively with their spacing members, if such are present, 80 may be called the "filler," may be made as is customary in shoe racks. In the rack shown four wooden verticals 44, nesting in the angles of the verticals 20, and resting upon the angles 42, form the corner members 85 for spacing and supporting the shelves. One practical construction of shelf is shown in the upper part of Fig. 1. The members 44 are slotted to receive the side members 46 and end members 48 of the shelf and the end members are bored part way through to receive the dowels or slats 50 which extend also through holes bored in the cross-brace 51. A tie rod 53 rests in a slot in the member 51 and holds the members 46 and 51 in close 90 contact.

95 A shelf embodying an important feature of my invention is shown in the lower part of Fig. 1 and a detail thereof is shown in Fig. 2. The shelf already described has the 100 disadvantage that the replacement of a broken dowel, even if the brace 51 be absent, necessitates taking the rack apart, since an attempt to spring the dowel into place often breaks it. I have shown in the lower shelf 105 how this difficulty may be avoided. One end member of the shelf is made in two parts 52, and 54, the latter of which fits in a rabbet 56 made in the former. The angle made by the rabbet in the part 52 is acute so that 110 it is impossible to slide the member 54 away from the member 52 by a purely horizontal movement lengthwise of the shelf. A spring latch 58 in the member 54 coacts with a bushing 60 in the member 52 to hold the member 54 against vertical movement relative to the member 52. It will be seen that the member 54 cannot be moved away from the member 52 without pressing back the spring latch 58 since the latch holds it against vertical 115 movement and the acute angle 56 holds it against horizontal movement. A number of holes 62 are bored horizontally in the combined members 52, 54 to a depth equaling the thickness of the member 54 and so that 120

130

they are half in the member 54 and half in the member 52. The end member 53' at the other end of the shelf may be made as usual, having correspondingly arranged holes bored 5 part way through it. In order to replace a broken dowel it is only necessary to press back the latch 58, lift the member 54, insert the new dowel in place and replace the member 54, allowing the latch 58 to spring back 10 into place. The members 44 are cut away as at 61 to facilitate removal of the element 54.

In a shelf formed entirely of dowels the dowels 63 at the edges of the shelf are generally made larger than those in the interior 15 and are frequently placed at a slight elevation in order to prevent spilling the contents. If desired the member 54 may be so shaped at its lower edge that the joint between it and the member 52 passes through 20 the holes occupied by these outside dowels, as above described. I prefer, however, to run this joint straight across, for the sake of economy in construction, and to bore the holes for these outside dowels as shown in 25 Fig. 1. New outside dowels may be inserted by lifting the member 54 upward entirely away from its adjacent member 52, which will lengthen the distance between the opposite end members of the shelf and allow the 30 dowels to be removed or replaced. The initial movement of the bar 54 will slide it inward over the dowels, but as soon as it has been raised to a sufficient height the dowels can be removed easily.

35 An inspection of Fig. 3 shows that the wooden vertical 44 does not entirely fill the space in the interior of the angle 20 so that the member 28 does not come in contact with it at all. The member 30 being entirely 40 outside the rack is of course not in contact with the wooden verticals 44. The bolts 38 and 40 are inserted through ample sized holes in the members 44, and there is no positive bonding between the filler and the steel 45 frame.

This feature is of considerable importance. The steel frame, as has been remarked, is entirely self supporting. It is contemplated that the length of the member 32 will be 50 so adjusted as to hold the pairs of verticals 20 relative to each other so as to effect a substantial fit of the interior wooden frame between the verticals at the ends of the rack. The wooden members of the rack are simply 55 supported upon the little shelves 42 and confined between the corner angle irons but are not positively bolted to any portion of the steel frame. The tubular members 26 project inwardly over the space included between the concave sides of the corner angle irons 20, and limit the upward movement 60 of the filler in case it should become loose. The corner angle irons limit the movement of the filler in four of the six possible directions, and the members 42 and 26 limit

it in the other two. All of these limitations of movement are by abutting contact and are independent of any bonding means between the metal and the wood. The shrinking and swelling of the wood which is inevitable in the atmospheric conditions which prevail in shoe factories, will therefore have no effect whatever upon the stiffness and strength of the rack as a whole. The steel frame will always be perfectly rigid and 70 even if the wooden members shrink to such an extent that they become very loose, the stability of the rack will not be affected. The omission of positive bonding between the metal and wooden parts of the rack actually 75 diminishes the difficulty due to shrinking and swelling. The rigid bonding of two materials having dissimilar reactions to the conditions to which they are to be subjected is always to be avoided, and in the rack 80 shown the wood can "come and go" in its own way under changing atmospheric conditions, and there is no tendency for the comparatively unvarying steel to pull the filler apart. 85

90 This construction is superior to heretofore used constructions in respect to the protection afforded to the wooden filler. If a rack the wood filler of which is bonded to its frame receives a severe shock, the resilient 95 yielding of the frame under the shock will tear loose the fastenings between the filler members and the frame and will strain and damage the filler. In a rack made according to my invention a shock to the steel frame, unless so severe as to deform the frame, will not injure the filler, since the only stresses which the frame can exert on the filler are compressive, and a wooden structure resists such stresses well. These stresses are small 100 at any one point, owing to the extended area of contact between the frame and filler. In a combined steel and wood rack built in accordance with the practice prevailing before the present invention, great stresses are localized at the points where the frame is fastened to the filler, and also at all the joints 105 of the filler. The situation of the filler in the rack of the present invention much resembles that of the wooden drawers in a 110 steel safe.

115 The novel method of constructing racks herein disclosed is an important aspect of the invention. The steel frame, except the strut-and-tie member, is erected in position, 120 and the wooden parts are separately assembled and may be held in assembled relation merely by a few brads. The assembled wooden parts are then dropped down in between the metal corner verticals of the end frames (which can be sprung apart slightly at the top to facilitate this operation), and the strut-and-tie member is then put in place, firmly holding the steel frame in position, 125 the said frame confining and maintaining 130

the wooden parts in proper relation to one another. The assembly of the rack is thus rendered very simple and rapid. The racks may be stored or shipped in knocked-down form, with the metal frames folded and the wooden fillers separated into their component shelves and other parts, and when needed they may be easily assembled by any unskilled person.

10 The old style steel-and-wood rack, in which the wooden shelves were separate members inserted in the frame, required very considerable time and skill in its assembly, as it necessitated a number of operations and it 15 was exceedingly difficult to keep the previously inserted shelves in position while inserting another one.

It is quite important to observe that 20 wooden shoe racks which have been damaged in their lower portions may be economically utilized as "fillers" in building a rack in accordance with the improvement in the art of making racks contemplated by this 25 invention and this novel method of building a rack, or in the present instance, of what may be termed rebuilding a damaged wooden rack, will now be described. It frequently happens that the base members of a rack 30 are broken or split by running into low obstructions not visible to the person who is propelling the rack, or by shocks transmitted through the casters in traversing rough floors. The substitution of new pieces 35 of wood for the shattered ones entails considerable expense and has to be done repeatedly. It is not unusual, in factories using wooden racks, to find at any time, many racks standing aside awaiting repair. The space required for even temporary storage 40 of damaged racks is an important consideration also. In accordance with my invention the lower portion of a rack injured in this manner will be cut off, leaving only the nest of corner verticals and shelves, or 45 what I have above designated as the "filler." A metal frame, such as I have shown, will then be built of such dimensions as to fit snugly around the nest of wooden shelves and the connecting member 32 will complete 50 a rigid metallic frame or cage within which the wooden filler will be confined. It is thus possible to obtain a rack which is better than the old one at the price of the steel frame only. The loss caused by the continual 55 repair and ultimate throwing away of damaged wooden racks, portions of which are usable in this manner, is thus avoided and a rack is secured which is almost indestructible and will last many times as long 60 as the original wooden rack.

Having described my invention and shown how it may be practiced, what I claim as new and desire to secure by United States Letters Patent is:

65 1. In a shoe rack, a metallic frame com-

prising a base and upstanding end portions and metallic bracing for said parts including a combined strut and tie member rigidly connecting said end portions near their upper ends whereby said frame is rendered 70 completely rigid and self supporting and a wooden filler mounted in the frame, said frame comprising frame members one or more of which is positioned directly in the path of movement of the filler from normal 75 position in any direction to obstruct such movement irrespective of bonding between the frame and the filler.

2. In a shoe rack, a metal base frame having upstanding verticals at its corners 80 formed of angle iron with their concave faces turned inward, metallic bracing for said base and verticals including a combined strut and tie member rigidly interconnecting said verticals near their upper ends 85 whereby a rigidly self-supporting metal frame is produced, and a filler having corner portions nested within the concavities of said angles and confined irremovably therein without bonding to the frame. 90

3. In a shoe rack shelf, a member having a slot-receiving seat and an acute angled rabbet, a removable slat retainer seated in the rabbet, and a latch constructed and arranged to prevent the sliding of said retainer over one face of said rabbet, the acute angle and latch being constructed and arranged to confine the retainer against movement over the other face of the rabbet. 95

4. In a shoe rack, a rigid structure having 100 end frames, two end members for a shelf mounted in said end frames, one of said end members having a socket to receive a dowel, and a third member having a seat corresponding to said first named socket, 105 and removably latched to the other end member.

5. In a shoe rack, the combination with a completely self-supporting metal frame comprising a rigid metal base having rigidly 110 connected therewith upstanding metal corner verticals presenting inwardly facing channels and rigidly interconnected by metal bracing rigidly secured to the ends near the top of the frame, of a shelf structure comprising interconnected wooden corner verticals supported and nesting in said channels. 115

6. In a shoe rack, the combination with a completely self-supporting metal frame 120 comprising a rigid metal base having rigidly connected therewith upstanding metal corner verticals presenting inwardly facing channels and rigidly interconnected by a metallic combined strut and tie brace member between the ends near the top of the frame, of wooden shelves supported from said verticals with their corners extending into said channels. 125

7. In a shoe rack, the combination with 130

a completely self-supporting metal frame comprising a rigid metal base having rigidly connected therewith upstanding metal corner verticals presenting inwardly facing channels and rigidly interconnected by metal bracing rigidly connected to the corner verticals near the top of the frame, of wooden shelves supported from said verticals with their corners extending into

10 said channels.

8. In a shoe rack, a completely self-supporting metal frame comprising a rigid metal base having rigidly connected therewith end frames each comprising two upper standing metal angle bar corner verticals presenting inwardly facing channels, said end frames being rigidly interconnected by a rigid metal brace structure comprising flat members engaging the angle bars of the respective end frames over a substantial vertical extent, whereby the brace structure holds the end frames against relative horizontal and vertical movement, and wooden shelves supported from said verticals with 25 their corners extending into said channels.

9. In a shoe rack, the combination with a metal frame comprising a rigid metal base having rigidly connected therewith upstanding metal corner verticals presenting inwardly facing channels, of a shelf 30 structure comprising interconnected wooden corner verticals supported and nesting in said channels.

10. That improvement in the art of making racks which consists in providing a shelf structure having interconnected wooden corner verticals, providing a completely self-supporting shelf enclosing metal corner verticals presenting inwardly facing channels, inserting the shelf structure within the metal frame with its wooden verticals supported and nesting in the channels of the metal corner verticals of the metal frame and confining the wooden verticals in said channels without bonding the shelf structure to the metal frame.

In testimony whereof I have signed my name to this specification.

HARVEY L. GLIDDEN.
